DOORCHECK

Marcus B. Hemingway, New Haven, Conn.

Application May 20, 1935, Serial No. 22,382

1 Claim. (Cl. 16—53)

This invention relates to an improvement in door-checks, and particularly to that class which includes a spring for closing the door, the object of the invention being to provide means simple 5 in construction and, therefore, not liable to be deranged, and positive in action.

The invention consists in the construction as hereinafter described and particularly recited in the claim.

10 In the accompanying drawing:

Fig. 1 is a front view of a door-check constructed in accordance with this invention and shown as applied to a door;

Fig. 2 is a vertical sectional view on an enlarged 15 scale;

Fig. 3 is a sectional view on the line 3—3 of Fig. 2;

Fig. 4 is a sectional view on the line 4—4 of Fig. 2; and

20 Fig. 5 is a perspective view of the piston, detached.

In carrying out this invention, a shell 10 is employed, which is provided with a bracket 11, by which it may be attached to a door. In the shell 25 is a cup-shaped piston 12 having a port 13 in the bottom, which is normally closed by a spring-valve 14. In one side is a vertical slot 15 and in the opposite side is an opening 16, and from the opening 16 a by-pass 17 extends to the bottom of the piston. The piston is supported in its downward position by a boss 18 formed in the bottom of the shell 10. Mounted in the shell, in line with the by-pass, is a screw 36 having a pointed end 37 extending into the by-pass.

35 Mounted upon a pin 19 attached to the piston is a roller 20, and entered into the back of the shell is a screw-plug 21 having a reduced end 22 which extends into the slot 15 in the piston and carries a roller 23.

The top of the shell is closed by a cap 24 and extending upwardly through this cap is a stud 25 of an actuator 26, which corresponds in diameter to the internal diameter of the piston, and 45 this actuator is formed with a spiral groove 27 into which the pin 19 extends, so that the roller 20 thereon will travel when the actuator is turned, as in the opening or closing of the door.

50 Affixed to the stud 25 is an operating-arm 28, which is pivoted to an operating-arm 29, which, in turn, is pivoted to a bracket 30, in the usual manner of door-checks of this type.

Within the piston is a spring 31 bearing upon 55 the bottom of the piston and against the lower

end of the actuator, and this piston is filled with fluid 32.

Preferably, around the casing at the upper end is a spring 33, one end 34 of which enters a recess for it in the casing, while the other end 35 is hooked over the arm 28.

As shown in Fig. 2 of the drawing, the parts are in the positions they assume when the door is in its closed position. Opening the door moves the arm 28 so as to turn the stud 25 and rotate the 10 actuator 26, causing the piston 12 to rise, this piston being held against rotation by the plug 21, and as the piston rises, the spring 31 is compressed and the fluid escapes through the port 13, the valve 14 yielding for free escape of the liquid, 15 so that the liquid passes into the bottom of the shell.

When the door is released, the expansion of the spring 31 will tend to force the piston downward, in which case the spring 14 closes the opening 13, 20 and the liquid is forced through the by-pass 17 and through the opening 16 into the piston. The area of this by-pass may be regulated by the screw 36, the downward movement of the piston rotating the actuator 26 and so moving the door to the 25 closed position, and this movement is accelerated by the spring 33.

This invention thus provides, with few parts, a door-check which will be positive in its action 30 and not liable to become deranged.

It will be understood by those skilled in the art that this invention may assume varied physical forms without departing from the inventive concept and the invention, therefore, is not limited to the specific embodiments herein chosen for illustration.

I claim:

A door-check comprising a shell adapted to be mounted upon a door, a cup-shaped piston 40 closely fitting said shell and axially movable therein, said piston formed on one side with a longitudinal slot and on the opposite side with an opening, means to prevent the rotation of the piston, a by-pass intersecting said opening, a 45 pin mounted in said piston opposite the slot, an actuator closely fitting said piston and formed with a spiral groove into which the said pin extends, said actuator being formed with a stud extending through the casing, arms connecting the 50 stud with the door-casing, a spring seated in said piston and bearing against the lower end of the actuator so as to be depressed thereby, and a valve-opening in the bottom of the piston.

MARCUS B. HEMINGWAY. 55
